(57) **CLAIM**

The ornamental design for a lamp, as shown and described.

DESCRIPTION

FIG. 1 is a bottom plan view of a lamp showing the design; FIG. 2 is a top plan view thereof;

FIG. 3 is a perspective view thereof;

FIG. 4 is a perspective view thereof, slightly rotated as compared to FIG. 3;

FIG. 5 is a side elevation view thereof;

FIG. 6 is a side elevation view thereof, slightly rotated as compared to FIG. 5;

FIG. 7 is a side elevation view thereof, slightly rotated as compared to FIG. 6;

FIG. 8 is a bottom plan view of another embodiment of a lamp showing the design;

FIG. 9 is a top plan view thereof;

FIG. 10 is a perspective view thereof;

FIG. 11 is a perspective view thereof, slightly rotated as compared to FIG. 10;

FIG. 12 is a side elevation view thereof;

FIG. 13 is a side elevation view thereof, slightly rotated as compared to FIG. 12;

FIG. 14 is a side elevation view thereof, slightly rotated as compared to FIG. 13;

FIG. 15 is a bottom plan view of another embodiment of a lamp showing the design;

FIG. 16 is a top plan view thereof;

FIG. 17 is a perspective view thereof;

FIG. 18 is a perspective view thereof, slightly rotated as compared to FIG. 17;

FIG. 19 is a side elevation view thereof;

FIG. 20 is a side elevation view thereof, slightly rotated as compared to FIG. 19;

FIG. 21 is a side elevation view thereof, slightly rotated as compared to FIG. 20;

FIG. 22 is a bottom plan view of another embodiment of a lamp showing the design;

FIG. 23 is a top plan view thereof;

FIG. 24 is a perspective view thereof;

FIG. 25 is a perspective view thereof, slightly rotated as compared to FIG. 24;

FIG. 26 is a side elevation view thereof;

(Continued)

FIG. 27 is a side elevation view thereof, slightly rotated as compared to FIG. 26; and,
 FIG. 28 is a side elevation view thereof, slightly rotated as compared to FIG. 27.
 The portions of the lamp shown in broken lines form no part of the claimed design.

1 Claim, 28 Drawing Sheets
